UNITED STATES PATENT OFFICE.

LEONARD DALE WILSON, OF OREGON CITY, OREGON.

VACUUM-CLEANER ATTACHMENT.

Application filed March 30, 1925. Serial No. 18,183.

The present invention relates to a device for cleansing Diesel engines, internal combustion engines, and other apparatus where there are deposits of foreign matter which must be loosened before removal, like the carbon deposits in hydrocarbon engine cylinders.

The objects of the invention include the following:

10 The combination of an air suction device with means for dislodging materials which may be drawn into the apparatus;

15 The attachment to a vacuum cleaner of a brush mechanism actuated conjointly with the suction pump of the vacuum apparatus;

20 A novel combination of brush members and suction apparatus whereby foreign matter loosened by the brush may be conveyed into a receptacle for such matter attached to said suction apparatus; and

25 A new article of manufacture comprising a vacuum cleaner apparatus and brush members combined therewith for increasing the efficiency and scope of operations of the vacuum cleaner.

These, and such other objects as may hereinafter appear are attained by the novel combination, construction and arrangement of the several elements which constitute the invention, one embodiment of which is illustrated in the accompanying drawing, in which—

30 Figure 1 is a schematic arrangement of the device, the parts generally shown in elevation;

35 Figure 2 is a longitudinal section; and

Figure 3 is an end view.

Like reference characters are used to designate similar parts in the drawing and in the 40 description of the device which follows.

Only so much of the device is shown as is required to illustrate its novelty. As the device is capable of employment upon different types of vacuum cleaners and has nothing to do with the internal structural arrangement of the vacuum cleanser proper, an illustration of such a cleanser is omitted from the several figures hereinabove described.

Comprising, as it does, an apparatus designed for cleansing carbon deposits from Diesel and internal combustion engines, it must be borne in mind that the structural arrangement of the embodiment may be modified to suit the special work for which the 55 apparatus is to be used, and therefore, the

description hereinafter given is general in its nature.

As illustrated, a flexible line or tube 10 of metal or other suitable material is provided for attachment to the suction vent of a vacuum cleaner, and the tube 10 serves as a pipe or conduit for the suction stream. In order to generate a suction force which is to be directed and controlled by movement of tube 10, a suction fan 11, is supplied. Such a member 60 is common to vacuum cleaners. The fan 11 is driven by an electric motor (not shown) or other prime mover to which it may be connected by a flexible connector, a chuck, or screw.

70 Disposed in the tube 10 upon suitable cross members, such as 10^a shown in Figure 2, is a second flexible conduit 10^b, preferably metal, concentrically arranged with respect to tube 10, and in which is disposed a cable 12. Said cable 12 is loosely connected by a flexible connection 12^a to fan 11, and rotates freely in conduit 10^b which rigidifies the cable or flexible shaft and precludes the accumulation of foreign matter thereon in the passage thereof 75 through the flexible tube 10. The speed of rotation of cable 12, is of course substantially identical with that of fan 11.

The outermost end of tube 10, designated 13, is of a truncated cone configuration or 80 funnel-like in its appearance. Within section 13 is disposed a stem or spindle 14 driven by cable 12. A thrust bearing 14^a on the inner end of spindle 14 prevents longitudinal movement of said spindle. It is usual 85 to dispose such thrust bearing 14^a upon one of cross members 10^a.

At the outer end of spindle 14 is a disc member 15, best shown in Figure 3, which 90 comprises a plurality of triangular brush members 15^a, preferably opposed or in the end to end position, and spaced apart by openings or vents 15^b, also triangular in configuration. The brush members 15^a comprise bristles of steel wire which bristles are 95 adapted to cleanse metallic or other surfaces coated with foreign materials and held there-to by oil, grease or other viscous deposits.

The reference numeral 16 refers to a 100 schematic illustration of the usual portions of a vacuum cleaner including the ordinary dust trapping bag motor and the like. Since 105 these portions of my improved cleaner are standard in construction and would be modified only in so far as would be necessary to 110

fit in with the mechanical shape which my cleaner assumes, no detailed illustration of this portion of the mechanism is believed to be necessary.

5 The device as described and illustrated, after being secured at the suction vent of a vacuum apparatus, is brought in contact at its brush end 15^a by proper manipulation of the flexible tube 10. Energy is fed to the motor 10 which conjointly sets in operation the suction fan 11 and the disc 15 connected to said fan by cable 12. Rotation of brushes 15^a loosens from any surface with which said brushes come in contact detachable matter. 15 Such loosened material is drawn through the vents 15^b into section 13, through tube 10, and

into the waste reservoir of the vacuum apparatus, which reservoir is emptied from time to time as occasion demands.

I claim:—

20 A vacuum cleaning machine comprising a suction fan, means for driving the said fan, a flexible suction conduit, a second flexible conduit positioned within the first mentioned conduit, a flexible shaft disposed within the 25 second conduit having one end operably connected to the fan and a brush assembly secured to the other end of the shaft and disposed within the end of the first mentioned conduit.

LEONARD DALE WILSON.
